RE-USABLE PALLET BIN

De Moine H. Frye, Detroit, Mich., assignor to
Leslie T. Swallow, Detroit, Mich.

Application April 26, 1948, Serial No. 665,213

3 Claims. (Cl. 229—23)

1

The invention relates broadly to new and useful improvements in reusable shipping and storage cartons or bins of fiberboard or the like.

When shipping small highly finished articles, it is conventional practice to pack a number of them in small cartons so that they are not damaged by jostling or handling. As a result, a large number of cartons usually is required for each carload shipment. It is desirable that these cartons be rugged in construction so that they can be used repeatedly, and it is also desirable that they be light in weight, since the shipper must pay freight charges on them as well as on the articles. Heretofore, cartons have been made both of wood and of cardboard. The wooden cartons are strong and durable in construction and consequently can be used over and over again; however, they are relatively expensive to manufacture and their relatively great weight makes shipping charges excessive. On the other hand, the cardboard cartons are relatively inexpensive to manufacture and are light in weight so that shipping costs are reduced to a minimum; however, they are easily torn and are quickly rendered unsuitable for use by ordinary abuse and handling during shipment. Usually they are used once and then discarded.

Another disadvantage of the conventional wooden carton arises in cases where a manufacturer of small parts ships them to an assembly plant consignee. The consignee must unpack the articles as soon as they arrive in order to permit immediate return of the cartons. This involves a great deal of unnecessary labor, since unpacking requires individual handling of the articles. Furthermore, the articles must all be handled again when they are used.

An important object of the present invention is to provide a cardboard carton that is light in weight, relatively inexpensive to manufacture, and strong and durable in use.

Another object of the invention is to provide a cardboard carton wherein the bottom is raised from the supporting surface and is not readily affected by moisture.

Still another object of the invention is to provide a carton of the above-mentioned character in which the parts are readily foldable or collapsible into compact bundles for return shipment.

Yet another object of the invention is to provide a cardboard carton which comprises separate interlocking sections uniquely constructed and associated so that a plurality of them can

2

be stacked together to provide a multilayered shipping and storage bin.

A further object of the invention is to provide a shipping and storage bin having similar sections which are interchangeable and can be individually replaced from time to time as required.

A still further object of the invention is to provide a shipping and storage bin in which the various layers can be formed progressively as the articles are packed therein.

A yet further object of the invention is to provide a shipping and storage bin in which the sections can be progressively disassembled and folded for return shipment as the articles are unpacked.

Another object of the invention is to provide a shipping and storage carton that is adapted to retain the articles from the time they are packed for shipment until such time as they are required for use, thus eliminating separate unpacking operations and multiple handling of the individual articles by the consignee.

Other objects and advantages of the invention will be apparent during the course of the following description.

In the drawing forming a part of this specification and wherein like numerals are employed to designate like parts throughout the same,

Fig. 1 is a perspective view showing carton sections stacked together to provide a four-layered storage bin;

Fig. 2 is an exploded perspective view showing the different sections of an individual carton; and

Fig. 3 is an enlarged, fragmentary, vertical sectional view taken on the line 3—3 of Fig. 2.

The carton embodying the instant invention is made in sections and in its preferred form comprises a supporting base 10, a bottom 12, a frame 14, a divider 16, and a cover 18 (Fig. 2). The base 10 preferably is made of wood, and the other sections of the carton preferably are made of fiberboard or the like. In this connection it should be noted that the term "fiberboard" is here employed to designate any conventional, relatively stiff and foldable fibrous sheet material such as cardboard, corrugated cardboard, pasteboard, and the like.

When the sections are assembled, the bottom 12 is supported by the base 10 and in turn supports the frame 14. Divider 16, which fits snugly within the frame 14 and is supported by the bottom 12, holds the former expanded and divides it into relatively small compartments. Cover 18 fits snugly over the frame 14. The

assembled sections may be held together in any desired manner, as by metal bands 20 shown in Fig. 1.

The only function of base 10 is to provide a firm surface for the bottom 12 and to support the assembled sections of the carton. In this connection it will be observed that the base 10 is substantially the same size and shape in plan as the bottom 12 so that it supports the latter solidly over its entire area. In order to facilitate handling, the base preferably is formed so that it can be picked up from below, and, if holding bands 20 are employed, it preferably is made with an open structure so that the bands can be wrapped around the carton sections without lifting or tipping the assembly. The base here shown is admirably suited for this purpose and comprises spaced parallel joists or runners 22 fastened together by a plurality of transverse slats 24.

The bottom 12 comprises a flat sheet of fiberboard 26 provided at its edges with flanges 28. These flanges 28 are separate from each other and are formed by fashioning the marginal portions of sheet 26 into flat loops and then fastening the opposite sides of the loops together. In the form of the invention here shown by way of illustration the loops are shown stitched together by a heavy thread; however, it is contemplated that any suitable fastening means such as staples or rivets be employed for this purpose. It will be observed that each of the flanges 28 has an upstanding rim 30 and a depending lip 32 and is integrally attached to the sheet 26 along a fold line here designated generally by the numeral 34.

When the bottom 12 is assembled in the carton, flanges 28 occupy positions normal to the plane of sheet 26 as shown in Figs. 2 and 3 so that the depending lip portions 32 overlie and fit snugly against the base 10. The latter holds the lip portions 32 raised from the supporting surface so that they are not required to sustain the weight of articles in the carton, and the lip portions hold the bottom 12 solidly associated with the base. However, since the flanges 28 are formed separately from each other, they can be readily folded flatly against the sheet 26 for return shipment when the bottom 12 is removed from the base 10. In this connection the most compact arrangement is obtained by folding one pair of opposed flanges 28 under the sheet 26 and the opposite pair of opposed flanges on top of the sheet. When the flanges 28 are folded in this manner, either the rim portions 30 or the lip portions 32 extend beyond the sheet 26, but, since the flanges lie flatly against the sheet, a large number of the bottom members 12 can be stacked together to form a compact bundle.

The frame member 14 comprises vertical walls 36 which may be integrally connected, as at 38, or flanged and glued or otherwise attached together, as at 40.

When the frame 14 is assembled in the carton the walls 36 are expanded as shown in Fig. 2 and rest on the bottom sheet 26 behind the upstanding rim portions 30. Thus, the frame 14 interlocks with the bottom 12, and the walls 36 are held solidly by the rim portions 30 against independent lateral movement.

The frame construction is such that it also can be reduced to a compact packet for return shipment when disassembled from the carton. It will be observed that one pair of opposite walls 36 are formed at substantially their middle with ver-

tical creases or fold lines 42. By reason of this arrangement, these walls can be folded inwardly and the frame collapsed by pressing the increased walls together.

5 The divider 16 comprises right angularly disposed partitions 44 and 46 which are suitably notched so that they interfit, as shown in Fig. 2. The divider 16 fits in the frame 14 and rests upon the bottom sheet 26. When the divider 16 is 10 thus positioned, partitions 44 and 46 divide the frame 14 into four relatively smaller compartments and abut walls 36 to hold the latter expanded and against the upstanding rim portions 30.

15 When removed from the frame 14 the divider 16 also can be collapsed to provide a compact packet for return shipment. This is done either by separating the partitions 44 and 46 and laying them flatly against each other or by folding the 20 partitions while still interfitted so that they lie flatly together.

Although two partitions 44 and 46 are here shown, it is to be understood that the divider 16 may comprise any desired number of partitions. As a practical proposition the number of partitions employed in any particular instance will vary according to the size of the carton and the number of compartments desired in the frame 14.

30 The cover 18 comprises a flat, substantially square sheet 48 of fiberboard provided at each edge thereof with a separate flange 50. These flanges 50 are formed by bending the fiberboard sheet from which the cover is made to provide fold lines 52 along the edges of the central portion 48, and each marginal portion extending from a fold line is bent back upon itself and stitched or otherwise fastened as at 54.

40 When the cover 18 is assembled on the carton the central portion 48 rests upon the upper edges of the frame 14 and divider 16 and the flanges 50 overlie and are held snugly against the walls 36 by bands 20.

45 On the other hand, when the cover 18 is disassembled, it may be flattened for return shipment either by spreading the flanges 50 so that they lie in the same plane as the central portion 48 or by folding the flanges inwardly against the central portion. If the latter alternative is adopted, one pair of opposed flanges preferably is folded under and the other pair over the central portion 48 to avoid overlapping at the corners.

55 From the foregoing it will be readily apparent that the carton is relatively inexpensive to manufacture and can be used for shipping any small article. The various sections are light in weight and maintain shipping costs at a minimum.

60 In fact, shipping costs are no higher when the instant carton is used than when conventional cardboard cartons are employed and are much less than when wooden cartons are used. Moreover, the sections are easily assembled or disassembled, and, after the articles are removed, they can be readily collapsed or folded and stacked together to form compact bundles for return shipment. In practice, the bottom members 12 are stacked with the covers 18 and the

65 frames 14 are stacked with the dividers 16, as these parts are similar in size and shape when collapsed.

70 Important advantages are achieved over the conventional cardboard cartons by making the 75 various sections separate and separable from each

other. For example, it is possible for the consignor to use the sections repeatedly as long as they are undamaged, and, if one section is torn or otherwise becomes unfit for use, it can be replaced without discarding the other parts of the carton. It is contemplated that the consignor maintain a reserve stock of the sections so that they can be easily and quickly replaced whenever necessary. Moreover, since the corresponding parts of the various cartons are identical and interchangeable, it is not necessary to maintain the parts of each carton separate from the parts of other cartons when they are returned to the shipper.

Another and primary advantage of the instant construction is that a plurality of the carton sections can be stacked together to provide a multilayered bin, as shown in Fig. 1. Assembling the parts in this manner achieves a further reduction in weight and a consequential reduction in shipping expense, eliminates unpacking and separate handling of cartons and facilitates shipment, transportation and storage of the articles. For example, when articles are shipped in the bin from a parts manufacturer to an assembly plant consignee, they can be stored in the bins. Then when the articles are to be used, the bins are moved to the assembly line, covers 18 are removed, and the various sections disassembled and folded or collapsed for return shipment as each successive frame is emptied.

To assemble the parts as shown in Fig. 1, one of the cartons is assembled on a base 10 and without the cover 18 in the manner hereinabove described. Other cartons are then assembled in the same manner on top of the first carton. When the desired number of the cartons have been stacked one upon the other and a cover 18 has been placed on top of the uppermost frame 14, the straps 20 are applied and secured in the conventional manner.

It will be observed that when the sections are assembled in this manner, the lower lip portion 32 of each bottom member 12 above the lowermost member overlies and interlocks with a frame 14 to hold all of the sections against relative lateral movement. When the straps 20 have been drawn tightly around the bin the assembled sections are held solidly together to provide a relatively strong and rigid structure. Since bottom flanges 28 and cover flanges 50 provide double thicknesses of fiberboard at the upper and lower corners and at spaced points along the sides of the bin, they form buffers or fenders which prevent the straps from cutting into the carton. Also the double thickness of the flanges makes them relatively rigid so that they substantially stiffen and reinforce the bin.

It will be apparent that under certain conditions, for example, in the case of relatively small cartons or bins, the divider 16 can be omitted from the assembly. When this is done, the articles packed in the frames 14 hold walls 36 expanded and against the surrounding flanges 28.

Also, under certain conditions the base members 10 may be omitted and the carton or bin supported entirely by the depending lip portions 32 of the lowermost bottom member 12. It will be observed that when the base is omitted the lip portions 32 hold the bottom of the carton or bin raised from the supporting surface and protect it from dampness. Manifestly, however, this arrangement is feasible only when the load is relatively light, since it is not desirable to break down the lip portions.

It is to be understood that the form of the invention herewith shown and described is to be taken as a preferred example of the same and that various changes in the size, shape and arrangement of parts may be resorted to without departing from the spirit of the invention or the scope of the appended claims.

Having thus described the invention, I claim:

1. A shipping and storage bin comprising a rigid base member having a plurality of separate bottom and frame members of foldable fiberboard sheet material stacked thereon, the margin portions of each bottom member being bent along fold lines and the portions extending beyond said fold lines fashioned into two flat loops extending in a single plane with one loop on one side and the other loop on the other side of the bottom, the sides of each loop being fastened together and the loops forming relatively rigid flanges adapted to overlie and retain the members thereabove and therebelow, the flanges extending along each side of each bottom member being separate from flanges on adjacent sides thereof and adapted to be positioned at right angles to the bottom or folded flatly and compactly against the bottom, each frame member consisting of upright walls fastened together and adapted to fit snugly behind the flanges of the bottom members and to be collapsed compactly together.
2. In a shipping and storage bin, separate bottom and frame members of foldable fiberboard sheet material, the marginal portions of each bottom member being bent along fold lines and the portion extending beyond each of said fold lines being fashioned into two flat loops extending in a single plane with one loop on one side of the bottom and the other loop on the other side of the bottom, the sides of the loops being fastened together and said loops forming relatively rigid flanges, the flanges at each marginal edge of the bottom being separate from the flanges at the other marginal edges of the bottom and said flanges adapted to be positioned at right angles to the bottom or folded flatly and compactly against the bottom, each frame member consisting of four walls fastened together and adapted to fit snugly behind the flanges of a bottom member and to be collapsed compactly together, the arrangement being such that a plurality of said bottom and frame members can be stacked alternately and when so stacked said walls seat edgewise against the bottom members behind the upstanding flange portions of said bottom members, the depending flange portions of said bottom members overlapping and surrounding the subjacent frame members to define a relatively rigid multilayered shipping and storage bin, whereby the various bottom and frame members in the bin are interchangeable so that the individual members can be replaced when necessary or desirable to maintain a complete bin structure.
3. In a shipping and storage bin, the subcombination comprising an individual bottom member of foldable fiberboard sheet material, the marginal portions of said bottom member being bent along fold lines and the portion extending beyond each of said fold lines being fashioned into two flat loops extending in a single plane with one loop on one side and the other loop of the other side of the bottom, the sides of each loop being fastened together and the loops forming relatively rigid flanges, the flanges extending along each side of the bottom being separate from

the flanges on adjacent sides of the bottom and all of said flanges adapted to be positioned at right angles to the bottom or folded flatly and compactly against the bottom.
